UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A VASE.

48,572.

Specification for Design.

Patented Feb. 15, 1916.

Application filed December 8, 1915. Serial No. 65,834. Term of patent 14 years.

To all whom it may concern:

Be it known that I, ANDREW J. SANFORD, a citizen of the United States, residing at Newark, Ohio, have invented a new, original, and ornamental Design for a Vase, of which the following is a specification.

In the drawing:

Fig. 2 is an end elevation of a vase embodying the invention.

I claim:

The design for a vase as shown.

ANDREW J. SANFORD.
